UNITED STATES PATENT OFFICE.

WILLIAM C. DREW, OF BROOKLYN, NEW YORK.

DESIGN FOR A CLOCK-FRONT.

SPECIFICATION forming part of Design No. 25,313, dated March 31, 1896.

Application filed January 31, 1896. Serial No. 577,622. Term of patent 7 years.

To all whom it may concern:

Be it known that I, WILLIAM C. DREW, a citizen of the United States, residing at Brooklyn, in the county of Kings and State of New York, have invented a new Design for Clock-Fronts, of which the following is a specification.

The leading features of this design for a clock-front consist in the design of the circular range of crosses around the frame and in the design of the convex number-ring having an inner scalloped edge and a vermiculated surface with leaflet projections.

In the accompanying drawings, Figure 1 is in elevation, and Fig. 2 a horizontal section.

The arms of the crosses A are widest at their outer ends and they stand in a circular range around the frame of the clock-front.

The number-ring B is convex and its inner edge is in front of the surface C, and this inner edge of the number-ring is scalloped at 2, and the surface is vermiculated, as represented at 3, and there are leaflet ornaments at 4.

The numbers on the ring are of ordinary character.

I claim—

The design of the clock-front substantially as described and represented.

Signed by me this 28th day of January, 1896.

WILLIAM C. DREW.
